United States Patent

Des. 238,111

Patented Dec. 16, 1975

238,111

MAGNETIC TAPE CASSETTE HOLDER

Richard Shyers, 737 Evergreen Parkway,
Union, N.J. 07083

Filed Nov. 12, 1973, Ser. No. 414,712

Term of patent 14 years

Int. Cl. D3—99

U.S. Cl. D87—1 D

FIG. 1 is a perspective view of a magnetic tape cassette holder showing my new design;

FIG. 2 is a bottom plan view; and

FIG. 3 is a section view taken along the lines 3—3 of FIG. 1.

I claim:

The ornamental design of a magnetic tape cassette holder, as shown.
